G. B. BEBOUT.
COLLAPSIBLE WICKET FOR DAMS.
APPLICATION FILED OCT. 31, 1913.

Patented Dec. 15, 1914.

UNITED STATES PATENT OFFICE.

GUY B. BEABOUT, OF WHEELING, WEST VIRGINIA.

COLLAPSIBLE WICKET FOR DAMS.

1,120,787.

Specification of Letters Patent. Patented Dec. 15, 1914.

Application filed October 31, 1913. Serial No. 798,431.

To all whom it may concern:

Be it known that I, GUY B. BEABOUT, a citizen of the United States of America, and resident of Wheeling, county of Ohio, and 5 State of West Virginia, have invented certain new and useful Improvements in Collapsible Wickets for Dams, of which the following is a specification.

This invention relates broadly to improvements in wicket dams, and specifically to a collapsible wicket for such dams.

The primary object of the invention is to provide a novel form of movable dam section or wicket, which may be readily moved from a reclining to an elevated position, and vice versa, irrespective of the pool level or head of water.

A further object is to provide a device of the character mentioned which is designed to utilize the current of the stream and static head of water in moving from either of its extreme positions to the other, and which consequently requires a minimum of applied power to effect the movements.

25 And a still further object is to provide a wicket which is adapted to collapse under the force or impact of a boat striking thereagainst and which, consequently, will not seriously damage such boat or be damaged 30 thereby.

With these and other objects in view, the invention resides in the features of construction, arrangement of parts and combinations of elements which will hereinafter be fully 35 described, reference being had to the accompanying drawings, forming a part of this specification, in which—

Figure 1 is a side elevation of the invention, the full lines showing the same occupying lowered position and the dotted lines showing the same in elevated position; and Fig. 2 is a perspective view of the same in elevated position.

Referring to said drawings, in which like 45 designating characters distinguish like parts throughout the several views—1 indicates a shutter which may be formed of timber or other appropriate material and which is free at both ends, neither of said ends being 50 hinged or otherwise connected to any fixed object. Pivottally connected to said shutter at a point intermediate the ends thereof is a frame by means of which it may be firmly supported in elevated position, as shown in 55 Fig. 2 and also as shown in dotted lines in Fig. 1. Said frame comprises, essentially,

one or more metal props 2, a pair thereof being preferably employed, and one or more metal anchors generally designated by numeral 3. Said props have a parallel disposition and are pivotally connected at their upper ends, as in bearings 4, to the downstream face of the shutter and are pivotally connected at their lower ends, as in bearings 5, to the foundation 6, so that when said shutter occupies its elevated position said props assume parallel inclined bracing positions with respect to said shutter.

Each anchor 3 is formed of two members 3^a and 3^b placed end to end and pivotally connected. The lower ends of the members 3^b are pivotally connected to the foundation 6, as in bearings 7 located at suitable points on said foundation and the upper ends of the members 3^a are pivotally connected to 75 said props 2, having suitable bearings, as 8, located in fixed position with respect to said props. As shown, each member 3^b is provided with an extension 9 having formed thereon a laterally directed arm 10 adapted 80 to engage the connected member 3^a on its downstream face and thus limit the extension movement of the members composing the anchor, preventing, for a purpose which will hereinafter be made apparent, said 85 members from assuming alined positions.

Mounted in a stationary position on the foundation 6 at a suitable point is a guard or sill 11 of timber or other suitable material against which the lower end of the 90 downstream face of the shutter abuts when the latter occupies elevated position and by which downstream movement of the lower end of the shutter is limited.

As is obvious, the wicket is maintained 95 stationary in its elevated position, not only by the force of gravity acting on the nearly vertical shutter, but also by the pressure exerted by the impounded water against said shutter. When it is desired to lower the 100 wicket, either a horizontal force sufficient to overcome the forces maintaining it upright may be applied in a downstream direction to the upper end of the shutter, or a force may be applied in an upstream direction to the lower end of the shutter. In either case said shutter is rotated counter clockwise on the adjacent ends of props 2 to a point where the said forces tending to maintain the shutter upright are overcome, 110 when, by gravity, the frame collapses, allowing the wicket to assume the lowered posi-

tion indicated in full lines in Fig. 1. As is obvious, when the said forces tending to maintain the shutter upright have been overcome, as above explained, the weight of the 5 shutter and frame causes the anchor members to close one upon the other, said members turning at their point of pivotal connection 12 and also rotating in their bearings 7 and 8. Due to the fact that said 10 members are prevented from assuming positions in direct alinement, little or no resistance to a prompt collapse of the anchor is offered when the shutter has been rotated to a point where the force of gravity and 15 the vertical component of the pressures due to velocity and static head of the water thereagainst tending to hold it upright have been overcome.

To elevate the wicket from its lowered 20 position, an elevating force is applied to the upstream end of the shutter, causing the props 2 to rotate in their bearings 5 until an elevation has been reached where the pressure of the water acting on the shutter 25 acts to swing or rotate the shutter on the bearings 4, whereupon rotation occurs at both the bearings 4 and 5 until the limit of upright movement has been reached. As is apparent, the force required to elevate the 30 wicket from its lowered position is that force which is requisite to overcome the force of gravity plus a continually diminishing force equal to the vertical component of the velocity and pressure heads acting upon the 35 shutter. And, as is further apparent, there is in the elevating movement a point where the resultant moment of all forces about the bearings 4 is clockwise, and, consequently, that from this point to the limit of said 40 movement no applied, or external, force is required to accomplish the elevation of the wicket.

From the foregoing it will be clearly apparent that when the wicket is struck from 45 the upstream side by a boat, log, or other heavy floating object, the wicket will thereby be caused to collapse, and that little or no injury can result from the impact.

It will be understood that by varying the 50 location of the bearings 4 on the shutter the force required to effect the tripping of the shutter and a resultant collapse of the

wicket may be regulated to practically any extent desired. Further it will be obvious that the wicket may be so designed that it 55 will be automatically tripped when the upper pool, or impounded water, rises above a predetermined elevation with respect to the lower pool. In other words, the bearings 4 may be so located that when the upper pool 60 reaches a predetermined depth, the shutter will be automatically tripped and the wicket collapsed.

Variations in the lengths of the props, and anchors, or either of them, and changes 65 in the locations of any or all of the various bearings may be resorted to for the purpose of regulating the inclination of the upright shutter and the amount of applied force requisite to effect the various movements of 70 the wicket.

Having thus described my invention, what I claim as new, and desire to secure by Letters Patent, is—

A wicket comprising, in combination with 75 a foundation, a shutter having both ends free and movable with respect to said foundation, props disposed on the downstream side of said shutter, said props having one end thereof pivotally connected to said shutter intermediate the ends of the latter and their opposite ends pivotally connected at a stationary point, said props being adapted 80 to support said shutter in an elevated position, means limiting downstream movement of the lower end of said shutter, and means anchoring said props against an elevating movement beyond a predetermined point; the last mentioned means comprising pivotally connected members adapted for folding 85 one upon the other, one of said members being pivotally connected to said props and the other of said members being pivotally connected to the foundation; and means for 90 preventing said members from assuming positions in alined relation.

In testimony whereof, I affix my signature in presence of two subscribing witnesses.

GUY B. BEBOUT.
